UNITED STATES PATENT OFFICE.

DAVID H. FINBERG, OF ST. LOUIS, MISSOURI.

SHOE-HEEL.

1,381,980.

Specification of Letters Patent. Patented June 21, 1921.

Application filed April 22, 1920. Serial No. 375,736.

To all whom it may concern:

Be it known that I, DAVID H. FINBERG, a citizen of the United States, residing at St. Louis, State of Missouri, have invented 5 certain new and useful Improvements in Shoe-Heels, of which the following is a full, clear, and exact description, reference being had to the accompanying drawings, forming a part hereof.

10 The present invention is directed to improvements in heels of women's shoes, particularly to what are known as French heels, though of course not necessarily restricted thereto, the invention being applicable as 15 well to heels of men's and children's shoes. The invention finds special application in the case of aluminum and other metallic heels which are usually formed with a bottom socket for receiving a plug to which the 20 lift is in turn secured either as an independent member or molded thereto as an integral part thereof. In the present embodiment of my invention the plug and lift are molded as a single piece, the same having embedded 25 therein a stiffener member through which is passed the screw (or nail) that directly secures the same to the heel. The object of the improvement is to provide a heel of the character referred to in which the stiffener 30 member of the plug (and lift) possesses the necessary rigidity to prevent the same from suffering any distortion or bending with the driving home of the screw by which the plug and lift are secured to the heel, thereby 35 insuring a firm and even contact between the engaging surfaces of the lift and tread of the heel, and eliminating the danger of the outer edges of the lift peeling or curling away from the tread. The advantages of 40 the improved heel construction will be better apparent from the following detailed description thereof in connection with the accompanying drawings in which—

Figure 1 represents a side elevation of a 45 ladies' shoe showing my invention applied thereto; Fig. 2 is a vertical middle longitudinal section through the heel; Fig. 3 is a front elevation of the heel with parts in section; Fig. 4 is a plan of the tread showing 50 the stiffener member, but with the lift and plug thereof removed; Fig. 5 is a bottom plan of the heel with parts broken away; Fig. 6 is a perspective of the lift and its plug detached from the heel; Fig. 7 55 is a perspective of the stiffener member detached; Fig. 8 is a sectional detail showing

a slight modification of the stiffener; and Fig. 9 is a perspective showing a cup form of stiffener.

Referring to the drawings, and for the 60 present to Figs. 1 to 7 inclusive, S, represents the upper of a conventional shoe for women, C, the counter of the shoe, and H, the heel. In the present embodiment of the invention the heel is hollow, being cast as 65 a metallic shell of aluminum or equivalent light material, the bottom or tread end of the heel being provided with a socket 1, having inwardly and upwardly converging bounding walls and a substantially flat roof 70 as shown. The said socket receives a plug 2 with which is integrally cast or molded the lift 3, a metallic stiffening member in the form of a spider 4 being embedded in the material (preferably vulcanized rubber) entering into the composition of said plug and lift. The arms of the spider 4 are formed 75 with outer terminal bent portions *a* which pass through the plug, the free ends of said bent portions being substantially flush with 80 the upper face of the plug or that directly engaging the roof of the socket 1. When the plug is fully inserted in the socket the free ends of the bends *a* rest substantially in 85 the corners formed by the intersection of the roof of the socket with the bounding walls thereof, the body of the spider being disposed substantially along the dividing plane between the plug 2 and the lift 3. The lift 3 engages the tread of the heel on 90 all sides as fully shown in the drawings. The spider is provided with a central perforated pocket *t* for receiving the head of the screw 5 by which the plug (and lift) is secured to the roof of the socket 1, there 95 being sufficient metal above the roof to take in the full length of the screw. To accommodate the screw, the lift is formed with an outwardly tapering central opening *h* the walls of which yield as the head of the screw 100 forces its way through the lift with the driving of the screw into the heel, the walls of the opening subsequently (that is, after the head of the screw has been driven into the socket *t*) expanding to their normal position and closing over the head. The plug 105 is preferably perforated (Fig. 6) to accommodate the screw, though the perforation is not absolutely necessary as the screw may drive its own way through the plug.

It will be seen from the foregoing that the stiffener 4 (with its bends *a*) is located

wholly within the confines of the socket 1, the bends *a* acting as struts or braces therefor when the screw 5 is driven home. The spider arms with their terminal bends *a* 5 form an arch or dome concaved toward the roof of the socket 1, the screw 5 passing through the crown of said arch and through the plug into the metal above the roof, and drawing the stiffener firmly to the roof of 10 the socket. The dome shape of the stiffener imparts to it a degree of stiffness such as to insure against sagging or concaving of the dome outwardly and hence insuring against outward concaving of the lift. In other 15 words, it insures against any possible curling or bending of the marginal portions of the lift away from the tread of the heel, the contacting surfaces of the lift and tread of the heel remaining permanently in firm and 20 uniform engagement throughout. The struts *a* engaging as they do the socket 1 at the corners formed by the intersection of the roof and bounding walls thereof can not spread with the driving of the screw 5 so that the 25 dome or arch which said struts contribute to form can not sag. The spider form of stiffener permits the rubber in the molding operation to flow freely between the arms 30 of the spider and through the perforation of the socket *t*; so that not only does the 35 stiffener become wholly embedded in the rubber, but the plug and lift portions 2, 3, become integrally united at all points except where separated by the solid portions of the 40 spider. In the form of the invention thus far described, the free ends of the bends *a* 45 emerge from the plug as it were, and directly engage the walls of the socket 1; but it would be within the scope of the invention to have the free ends of the bends terminate beneath the upper surface of the plug so as to be 50 wholly embedded in the rubber. Such a modification is shown in Fig. 8, where the bends *a'* of the spider 4' do not emerge from the plug, but terminate in close proximity to the upper surface thereof. Again, in lieu 55 of a spider-form of stiffener I may substitute a cup-shaped member conforming in outline to the contour of the bounding walls 60 of the socket 1, the roof and walls of the cup being perforated to allow the rubber to flow freely through the perforations and integrally unite the plug to the lift. Such a 65 modification is illustrated in Fig. 9 where the stiffener 10 is shown embedded in the plug indicated by dotted lines to better bring out the shape of the cup. The cup 10 is nothing more or less than the spider 4 with the spaces between the arms filled in with metal, the whole being perforated to allow for the free flow of the rubber therethrough. The spider form of the stiffener is perhaps to be preferred because lighter and cheaper (having less metal) and being substantially 70 of equal stiffness with the cup form shown in

Fig. 9. The arch or dome of the stiffener spider (or cup) is herein shown substantially flat, but I do not wish to be limited to any particular form of arch. Neither do I wish to be limited to a plug and lift integrally united, as they may be secured together in other ways. In the examples before us the medial portion of the stiffener is disposed along the dividing plane between the plug proper and the lift, but a slight variation from this plane would not constitute a departure from the invention, and any claims imposing this limitation should be interpreted to include positions on either side of said dividing plane. 75

Having described my invention what I claim is:

1. In combination with a heel provided with a socket leading from the tread of the heel, a lift for the heel, a plug coupled to the lift and secured in the socket, and a stiffener member embedded in the lift and plug, the outer portions of the stiffener terminating within the compass of the confines of the socket and bent toward the roof of the socket 90 sufficiently to communicate thereto the stresses imposed by the weight sustained by the heel.

2. In combination with a heel provided with a socket leading from the tread of the heel, a lift engaging the tread around the socket, a plug integrally united to the lift and secured in the socket, and a stiffener member embedded between the lift and plug, the outer portions of the stiffener being directed toward and engaging the roof of the 95 socket.

3. In combination with a heel provided with a socket leading from the tread of the heel, a lift engaging the tread around the 105 socket, a plug integrally united to the lift and secured in the socket, and a stiffener member embedded in the plug and arched toward the socket, the marginal edges of the stiffener being disposed adjacent the upper 110 face of the plug or that engaging the roof of the socket.

4. In combination with a heel provided with a socket leading from the tread of the heel, said socket having a substantially flat 115 roof and bounding walls intersecting said roof, a plug inserted in the socket and secured to the roof thereof, a lift integrally united to the plug and engaging the tread of the heel around the socket, and a stiffener 120 member embedded in the material composing the plug and lift and having a medial portion disposed substantially along the dividing plane between the plug and lift, the outer portions of the stiffener being bent 125 toward and engaging the roof of the socket at the points of intersection of said roof with the bounding walls of the socket, and confined wholly within the compass of the boundaries of the socket.

5. In a heel of the character described, a combination plug and lift, and a stiffening spider embedded therein, the arms of the spider terminating in bends passing through the plug and terminating at the upper surface thereof.
6. In combination with a heel provided with a socket leading from the tread of the heel, a lift for the heel, a plug coupled to the lift and secured in the socket, and a stiffener member disposed along the plane of division between the plug and lift and confined within the boundaries of the socket, the outer portions of the stiffener penetrating the plug and operating as struts to take up the stresses imposed on the stiffener.
7. In combination with a heel provided with a socket leading from the tread, an attachment comprising a plug and a lift, the plug entering the socket and the lift engaging the tread around the socket, and an arched or dome-shaped stiffener member embedded in the plug and lift, the outer ends of the stiffener communicating the stresses imposed on the stiffener to the walls of the socket.

In testimony whereof I affix my signature, in presence of two witnesses.

DAVID H. FINBERG.
